TUMBLER OR SIMILAR ARTICLE

Carl C. Kohl, Pittsburgh, Pa., assignor to Bryce Brothers Company, Mount Pleasant, Pa., a corporation of Pennsylvania

Application January 24, 1955, Serial No. 34,181

Term of patent 7 years

(Cl. D36—8)

Fig. 1

Fig. 3.

Figure 1 is a perspective view of a tumbler or similar article, showing my new design;

I claim:

The ornamental design for a tumbler or similar article, as shown.
